WASHING AND IRRIGATING DEVICE

Willie Mae McFarland and Artie F. McFarland,
Houston, Tex.

Application December 26, 1939, Serial No. 310,880

2 Claims. (Cl. 123—229)

This invention relates to a device for the purpose of irrigation or washing of relatively inaccessible regions and particularly to a means whereby a medicated liquid may be supplied for such purposes.

The general object of this invention is to provide a device of the character referred to in which the medicament may be readily added in the exact proportion desired before the washing or irrigation begins.

It is the further object of this invention to provide a device of the type set forth which may be permanently mounted upon a wall or other support and which, when not in use, may be enclosed in such a manner as to present an attractive exterior appearance.

The further object of this invention is to provide a device of the type set forth in which the proportion of hot and cold liquid employed may be set and allowed to remain permanently, subject only to resetting as and when desired.

Another object of this invention is to provide a device of the type referred to in which the proportion of hot and cold liquid employed may be permanently set, together with a means whereby such proportion may be varied from the permanent setting temporarily without, however, disturbing the parts which determine the permanent setting.

Another object of this invention is to provide a device of the type set forth which may be contained within a cabinet having an attractive exterior appearance.

With the above and other objects in view, one embodiment of this invention is set forth in the accompanying drawings and the following description:

In the drawing:

Fig. 1 is a vertical cross-section taken through a device constructed in accordance with this invention.

Fig. 2 shows a vertical cross-section through the same device but taken at right angles to Fig. 1.

Fig. 3 is a horizontal cross-section of the same device taken along the line 3—3 of Fig. 2.

Fig. 4 is an enlarged view, partly in plan and partly in horizontal cross-section illustrating the mixing valve arrangement as embodied in this invention and showing a slight modification of the form set forth in Figs. 1, 2 and 3.

Fig. 5 is a vertical cross-section through the central portion of the device illustrated in Fig. 4.

Fig. 6 is a horizontal cross-section through the

device shown in Fig. 5 taken along the line 6—6 of Fig. 5.

In the embodiment illustrated in Figs. 1, 2 and 3, the cold and hot liquid will be supplied to the device through suitable means such as the pipes 1 and 2. These two pipes are connected through suitable fixtures to the mixing valve 3. In Fig. 4, there is shown a modification in which an extra valve 4 is inserted in one of these lines and an extra valve 5 in the other so that by means of these two valves the volume and proportion of hot and cold liquid may be adjusted and set.

The mixing valve 3 is of the plug type, the plug being in tapered form as shown at 6 and being controlled by a handle 1 of conventional design. This plug, as shown in Figs. 4 and 5, is provided with a channel 8 extending around the plug substantially two-thirds or more of its circumference. Leading from the cold and hot supply into the valve plug chamber are passageways 9 and 10 for conducting the cold and hot liquid to this chamber. The channel 8 is arranged to register with the openings 9 and 10 and also with an outlet opening 11 from the said chamber, said outlet opening leading into a special T-fitting 12. It will be seen that when the valve 3 is in the position shown in Fig. 4, no liquid may flow through either the passage 9 or the passage 10 into the passage 11, and assuming that the pressure is the same in the hot and cold supply, as it normally would be, there would be no flow whatever through the mixing valve 3.

If the handle of this mixing valve 3 be now turned to the right, as seen in Fig. 4, the left end of the channel 8 would shortly begin to register with the inner end of the passage 11 and liquid would begin to flow into this passage 11. There would be more liquid flowing from the liquid supply 2, however, than from the liquid supply 1 in such instance, because the liquid supply 2 would have a shorter distance to travel. Furthermore, at about the time the passage 11 begins to register with the passage 8, the passage 9 would begin to be slowly cut off so that more and more liquid would flow from the supply 2 and less and less from the supply 1.

If the handle be turned still further, the passage 9 will again be uncovered and may be uncovered to such an extent that an equal amount of liquid will flow from each liquid supply.

In the manner just related, any desired proportion of hot and cold liquid may be supplied to the passage 11.

The T-fitting 12 is provided with an outlet 13

adapted to receive a hose 14 and also with an upstanding portion 13', the upper end of which extends through the bottom 15 of a liquid reservoir within the cabinet 16, this reservoir being designated by the numeral 17.

The part 13' is secured within the opening in the bottom of the reservoir 17 by any suitable means, such as the customary lock nut and gasket arrangement.

The cabinet 16 just referred to, in addition to the liquid reservoir 17 in its upper end, provides a compartment 18 in its lower end in which the hose 14 and other accessories may be stored. The front of this compartment 18 is provided with an opening 19, and the entire cabinet is adapted to be closed by means of a cover 20 pivotally mounted on pivots 21 carried by the side walls of the cabinet 16. The cabinet may be securely mounted upon a wall or similar support by means of bolts 22.

The reservoir 17 is provided with an overflow pipe 23 so that when an excessive amount of liquid accumulates therein, it will overflow into the lower compartment. The lower compartment is formed with an opening 24 in its bottom wall so that any such overflow liquid may drain out. It is contemplated in this instance that the cabinet will be placed above a bathtub or lavatory or some similar receptacle which will serve to catch such overflow liquid, but it is within the purview of this invention to provide a special drain pipe for receiving such liquid and conducting it to a suitable place.

Referring again to the connection between the part 13' and the reservoir 17, it will be seen that a cap 25 is secured to the upper end of this fitting and that this cap has lateral outlets 26 therefrom and an upper outlet 27. The outlet 27 is adapted to be closed by an upwardly movable valve element 28 carried within the cap. This valve element, when moved to its upper position, will close the opening 27, but is incapable of moving down far enough to close off the part 13' against lateral flow through the outlets 26. In order to guard the opening 27 and to prevent any spray or jet upwardly through this opening which might pass out of the top of the reservoir 17, there is provided a guard 29 over the opening 27.

The hose 14 may be closed whenever desired by any suitable clamping device 30, and carries on its free end a nozzle 31 of any desired characteristics.

In operation, if the modification shown in Fig. 4 is employed, the mixing valve 3 may first be turned so that both hot and cold liquid supplies are wide open. The valves 4 and 5 may then be adjusted until the liquid being supplied to the nozzle 31 is of exactly the desired temperature. This adjustment need not be disturbed unless and until it is desired to change the temperature of the liquid supply to the nozzle, or unless and until the temperature of the hot or the cold supply changes. In this form, the valve 3 may then be used simply as a cut off valve by turning it either to fully open or fully closed position as desired, or it may be operated as a proportioning and mixing valve to vary the temperature of the liquid supplied to the nozzle from that for which the valves 4 and 5 have been set. This latter variation would of course not disturb the setting of the valves 4 and 5.

For the purpose of adding a medicament to the liquid supplied to the nozzle, a liquid supply may first be introduced into the reservoir 17 by simply closing the shut off 30 and opening the liquid supply to fill the reservoir 17. When the required amount of liquid is in the reservoir 17 the medicament may be added and mixed, the liquid supply being shut off in the meantime. During the flowing of liquid into the reservoir 10 the valve 28 will be forced upwardly to close the valve 27 and prevent the spraying or jetting of high pressure liquids out through the top of the reservoir. The liquid will enter the reservoir 15 through the openings 26. When the liquid is drawn from the reservoir to the nozzle, the valve 28 will move away from its seat, thus permitting free flow of liquid from the reservoir.

One other function of the reservoir 17 is that if it be desired to supply liquid from the liquid supply directly to the nozzle, and the liquid from the liquid supply flows slightly faster than the nozzle can dispense the liquid without increasing the pressure, the excess liquid may flow up into the reservoir, the same serving in such 20 instance as a surge chamber.

When not in use, the hose 14 and the nozzle 31 together with other possible accessories may be stored within the compartment 18 and the cover 20 raised to completely enclose the various 25 parts and providing a neat and attractive exterior appearance.

It will be seen from the foregoing that a device has been provided which is capable fully of carrying out all of the objects hereinabove set forth with respect to its utility, and which, when not in use, may be entirely enclosed so as to present a neat and attractive appearance.

Having described our invention, we claim:

1. In a device of the character described, a liquid supply, a nozzle, means connecting said liquid supply to said nozzle, a means for shutting off the flow of liquid to said nozzle, a reservoir connected between said last mentioned means and said liquid supply, there being a relatively small lateral opening and a relatively large vertically directed opening between said liquid supply and nozzle on the one hand and said reservoir on the other, a valve operable by pressure of incoming liquid to said reservoir for closing said relatively large vertically directed opening when water is flowing into said reservoir to cause said water to flow laterally and at a relatively slow rate into said reservoir, said valve being movable by downward flow from said reservoir to open said relatively large vertically directed opening and permit free flow of liquid from said reservoir through said last mentioned opening to said nozzle.

2. In a device of the character described having a surge chamber, means for controlling flow of liquid to and from said surge chamber, said means comprising a member having a lateral opening of relatively small size and a vertically directed opening of relatively large size into said reservoir, and means operable by the pressure of liquid flowing into said reservoir for closing said relatively large vertically directed opening during the inflow of liquid and movable to open position by the outflow of liquid from said reservoir to permit free flow of such liquid.
